DOUBLE DESK

Anton J. Valic, 183 Elmhurst, Elmhurst, Ill. 60126

Filed Apr. 14, 1970, Ser. No. 22,424

Term of patent 14 years

Int. Cl. D6—06

U.S. Cl. D33—7

FIG.1

FIG.2

FIG.3

FIG.4

FIG.6

FIG.5

FIG. 1 is a front perspective view of a desk embodying my invention;

FIG. 2 is a top plan view of the desk of FIG. 1;

FIG. 3 is an end elevational view of a desk embodying my invention taken along the line 3—3 of FIG. 2;

FIG. 4 is a front elevational view of the desk of FIGS. 1 through 3;

FIG. 5 is an end elevational view taken along the line 5—5 of FIG. 2; and

FIG. 6 is an elevational view along the line 6—6 showing the side of the desk opposite FIG. 4.

I claim:

The ornamental design for a double desk, as shown.
